COTTON SAMPLE SELECTING DEVICE

George E. Gaus, Washington, D. C., assignor to
 Henry A. Wallace, Secretary of Agriculture of
 the United States of America and his suc-
 cessors in office

Application January 17, 1939, Serial No. 251,365

9 Claims. (Cl. 19—156)

(Granted under the act of March 3, 1883, as
 amended April 30, 1928; 370 O. G. 757)

This application is made under the act of March 3, 1883, as amended by the act of April 30, 1928, and the invention herein described and claimed, if patented, may be manufactured and used by or for the Government of the United States of America, for governmental purposes without the payment to me of any royalty thereon.

My invention relates to a new and useful device in combination with cotton gins or condensers having means for producing a continuous ribbon-like separation of the lint cotton bat discharged from the condenser.

One of the objects of this invention is to sever and deposit selected quantities of one of the ribbon-like bats issuing from the condenser, to obtain an average representative sample of each bale of cotton after it is ginned and before the same is baled.

Another object of this invention is to provide means for the separation and collection of integral portions of the lint cotton bat without disturbing the felted arrangement of the cotton fibers comprising the separated portion of the lint cotton bat.

A further object of this invention is to provide means for disposing of the portions of the lint cotton bat not selected for the representative sample.

A still further object of this invention is to obtain a sample from the lint cotton initially composing the completed bale.

The following description, considered together with the accompanying drawings, will fully disclose this invention, its constructions, arrangements, and operations of parts, and further objects and advantages thereof will be apparent.

In the drawings:

Figure 1 is a plan view illustrating an embodiment of my invention in combination with a cotton condenser.

Figure 2 is an end elevation of Figure 1.

Figure 3 is a fragmentary end view of my invention illustrating the mechanism in operative position for accumulating a selected portion of a representative sample of the lint cotton.

Figure 4 is a fragmentary end view of my invention illustrating the mechanism in operative position for discharging the unselected portion of the lint cotton into the cotton bale press-box.

Figure 5 is an enlarged fragmentary end view of the lint cotton separator mechanism similar to Figure 2, looking at the opposite side of the device.

Referring with more particularity to the draw-

ings in which like reference characters designate like parts, the numeral 1 designates suitable frame work of a cotton condenser which supports the condenser drum 2 that condenses, divides, and compresses the lint cotton into bat form after 5 being ginned and before being passed into the press-box for baling. The numeral 3 designates an imperforate band encircling the condenser drum 2 suitable for the purpose of longitudinally dividing the lint cotton bat delivered by the condenser drum 2. Extending outwardly from one side of the condenser drum 2 is a lint flue 4, leading from the condenser, while the other side is provided with lint slides 5 and 6. Lint slide 5 conveys that portion of the divided compressed 10 lint cotton bat 5A not operated upon by the cotton sample selecting device, from the cotton condenser into the cotton bale press-box 7. Lint slide 6 conveys that portion of the divided compressed 15 lint cotton bat 6A which is operated upon 20 by the sample selecting device. At the upper end of the condenser and adjacent to the condenser drum 2, is the usual compress roller 8, beneath which the cotton on the condenser drum 2 is passed and pressed into compact form before 25 passing down the lint slides 5 and 6.

My improved sample selecting device, as illustrated in Figure 1, is supported by projecting arms 9, 9 secured to the framework 1 of the condenser. Lint slide 6, having an inclined upper 30 portion, a curved center portion and a substantially vertical lower portion, is supported by upright frame members 10, projecting arms 9, 9 and cross members 11, 11 and 12, 12 secured to the framework 1. Beneath the lint slide 6 a sample box 13 is located for the collection of the accumulated lint cotton forming the representative sample of the gin bale. Shaft 14 is mounted parallel to the surface of lint slide 6 for rotation in suitable bearing structures supported by 35 the projecting arms 9, 9, and is driven by the belt 15 which passes over pulley 16 fixed to said shaft 14 and over the driver pulley 17 fixed to the condenser drum shaft 18. Arms 19 and 20 are pivoted at their lower ends to shaft 14, and 40 they are connected by transverse bars 21 and 22. A plate 23, attached to the transverse bars 21 and 22, conveys the lint cotton delivered from the doffer roller 24 to the chute 25 for deposition in the bale press-box 7. The doffer roller 24, provided about its circumference with resilient flexible flaps 26 longitudinally secured in spaced relation, has its shaft 27 rotatably mounted between the upper ends of the arms 19 and 20. Said roller 24 is continuously driven, in a counter- 45 50 55

clockwise direction (Figures 2, 3, and 4) by belt 28 which passes over a pulley 29 fixed to shaft 27 and over the driver pulley 30 fixed to shaft 14. The arms 19 and 20 can be swung about shaft 5 14 in a counter-clockwise direction (Figures 2, 3, and 4) by means of lever 31 attached to the arm 20, thus carrying the roller 24 away from the lint slide 6, as viewed in Figures 2 and 3. An abutment, such as eccentric stud 32 secured on 10 one of the arms 9, 9 in line with arm 29 permits regulation of the amount of pressure exerted by doffer roller 24 when in cooperative relation with lint slide 6.

An extending heavy plate 33, provided with a 15 corrugated resilient lip 34 at its outer end, is mounted below the roller 24 and is adapted to contact the slide 6 in advance of said roller, operating in conjunction with the roller and the lint slide 6 to transversely rend a portion of the bat that might be caught therebetween. The plate 33 is carried by rod 35 pivoted between bars 20 37 and 38 which are attached, respectively, to the arms 19 and 20. An adjustable abutment, such as set screw 39 resting on bar 37 (Figure 5) 25 mounted on a lug extension 36 of plate 33 permits regulation of the thrust of the lip 34 against the lint slide 6. The lip 34, while limited in a downward movement by the set screw 39, is free to move upward a short distance when forced 30 against the lint slide 6; the unbalanced weight of the plate 33 being depended upon to hold the cotton bat between the lint slide 6 and the lip 34.

A cylindrical bar 43 is carried at the lower end 35 of a plate 40, or any other suitable means, suspended from trunnions 41 and 42, which trunnions are pivoted on extensions of the cross members 12, 12. The member 43 is positioned so that its path of movement intersects an arc 40 of the path of relative movement between the doffer roller 24 and the slide 6.

The operation of this invention is as follows:

The lint cotton bat delivered from the condenser drum 2 is preferably divided longitudinally into two parts; a wide portion 5A which is 45 continuously conveyed by lint slide 5 into the cotton bale press-box 7 and a narrower ribbon-like portion 6A which is conveyed by lint slide 6 into position to be operated upon by my cotton sample selecting device.

50 When the doffer roller 24, together with the plate 33, are in their extreme positions away from the lint slide 6 (Figure 3) the ribbon-like lint cotton bat passes from the condenser drum 2 on the lint slide 6 into the sample box 13. When a sufficient quantity of the lint cotton bat 55 has been accumulated in the sample box 13, the lever 31 is actuated to swing the doffer roller 24 and plate 33 toward the lint slide 6 (Figure 4).

At the end of this movement the corrugated 60 resilient lip 34 forcibly contacts and holds the cotton bat on lint slide 6 in advance of the flaps 26 of doffer roller 24 preventing upward movement by rotating doffer roller 24 of that portion of the bat below the lip 34. Since this roller 24 is rotating against the cotton bat in a direction away from the lip 34, a transverse severance of the cotton bat results. When this severance takes place, the rotating flaps 26 pass the upper conterminous severed end of the cotton bat over the doffer 65 roller 24 onto the plate 23 and the chute 25 for conveyance of the oncoming cotton bat, being delivered by the condenser drum 2 (Figure 5), to the bale press-box 7 (Figure 4). The device is operated in this position (Figure 4) until it is 70 desired to remove another portion of the cotton 75

bat as a component part of the desired representative sample. To initiate this phase of the sampling process the lever 31 is again actuated to swing the doffer roller 24 with the plate 33 in a direction away from the lint slide 6. The oncoming cotton bat passing over the doffer roller 24 is elevated from the lint slide 6 with the doffer roller 24 thus coming into contact with the cylindrical bar 43. When the doffer roller 24 passes beneath the cylindrical bar 43, said bar 10 is rotated with the plate about its pivot. The bar 43 then swings back towards its normal vertical position exerting pressure on the sagging portion of the cotton bat suspended between the doffer roller 24 and the lint slide 6. This pressure, in addition to the continuous operation of roller 24 on the cotton bat, is sufficient to cause a transverse separation of the cotton bat. The severed end of the oncoming bat drops back against the lint slide 6 for conveyance to the sample box 13. The severed end of the cotton bat remaining on the doffer roller 24 is propelled forward onto the plate 23 for conveyance on chute 25 to the bale press-box 7.

It is readily apparent from the foregoing description that an average representative sample of a bale of cotton may be obtained during the process of ginning by alternately swinging the continuously rotating doffer roller and its associated parts at predetermined intervals for disengagement and engagement of the doffer roller with the lint slide 6, to cause longitudinal integral portions of the cotton bat desired as component parts of the representative sample to be deposited in one container and the portions of the cotton bat not desired as part of the representative sample to be deposited in another container.

It is to be understood that this invention may be modified by relocating the point about which the doffer roller and its associated parts pivot with respect to the lint slides, or by using other means to rotate the doffer roller, such modifications being within the scope of one merely skilled in the art.

Having thus described my invention, I claim:

1. In combination with a cotton condenser having means to separate cotton issuing therefrom into a plurality of continuous ribbon-like bats; a lint slide to guide one of said ribbons as a sampleable ribbon in a direction different from that of the remaining output of said condenser; means including the lint slide to alternately deliver portions of said sampleable ribbon to receptacles, one being a sample receptacle; and means to selectively separate said ribbon into portions for alternate delivery to said receptacles.

2. In combination with a cotton condenser having means to separate cotton issuing therefrom into a plurality of continuous ribbon-like bats; a lint slide to guide one of said ribbons as a sampleable ribbon in a direction different from that of the remaining output of said condenser; a cylinder rotatably supported parallel to and in front of said slide; means for varying the distance between said cylinder and said slide; and an arm depending below and coactable with said cylinder and said slide to transversely rend a portion of cotton bat therebetween.

3. In combination with a cotton condenser having means to separate cotton issuing therefrom into a plurality of continuous ribbon-like bats; a lint slide to guide one of said ribbons as a sampleable ribbon in a direction different from

that of the remaining output of said condenser; a cylinder having a friction surface rotatably supported parallel to and in front of said slide; means for varying the distance between said cylinder and said slide; and an arm depending below and coactable with said cylinder and said slide to transversely rend a portion of cotton bat therebetween.

4. In combination with a cotton condenser having means to separate cotton issuing therefrom into a plurality of continuous ribbon-like bats; a lint slide to guide one of said ribbons as a sampleable ribbon in a direction different from that of the remaining output of said condenser; a cylinder rotatably supported parallel to and in front of said slide; resilient, flexible flaps longitudinally secured in spaced relation about the circumference of said cylinder; means for varying the distance between said cylinder and said slide; and an adjustable arm depending below and coactable with said cylinder flaps and said slide to transversely rend a portion of cotton bat therebetween.

5. In combination with a cotton condenser having means to separate cotton issuing therefrom into a plurality of continuous ribbon-like bats; a lint slide to guide one of said ribbons as a sampleable ribbon in a direction different from that of the remaining output of said condenser; a cylinder rotatably supported parallel to and in front of said slide; resilient flexible flaps longitudinally secured in spaced relation about the circumference of said cylinder; means for varying the distance between said cylinder and said slide; and a bar suspended parallel to said cylinder in the path of relative movement between said cylinder and said slide.

6. In combination with a cotton condenser having means to separate cotton issuing therefrom into a plurality of continuous ribbon-like bats; a lint slide to guide one of said ribbons as a sampleable ribbon in a direction different from that of the remaining output of said condenser; a cylinder rotatably supported parallel to and in front of said slide; means for rotating said cylinder; resilient flexible flaps longitudinally secured in spaced relation about the circumference of said cylinder; means for selectively varying the distance between said cylinder and said slide; and an arm depending below said cylinder coactable with said flaps and said slide to transversely rend a portion of cotton bat therebetween.

7. In combination with a cotton condenser having means to separate cotton issuing therefrom into a plurality of continuous ribbon-like bats; a lint slide to guide one of said ribbons as a sampleable ribbon in a direction different from that of the remaining output of said condenser; a cylinder rotatably supported parallel to and in front of said slide; resilient flexible flaps longitudinally secured in spaced relation about the circumference of said cylinder; means for varying the distance between said cylinder and said slide; and an arm depending below said cylinder having a corrugated resilient end coactable with said flaps and said slide to transversely rend a portion of cotton bat therebetween.

8. In combination with a cotton condenser having means to separate cotton issuing therefrom into a plurality of continuous ribbon-like bats; a lint slide to guide one of said ribbons as a sampleable ribbon in a direction different from that of the remaining output of said condenser; a cylinder rotatably supported parallel to and in front of said slide; resilient flexible flaps longitudinally secured in spaced relation about the circumference of said cylinder; means for varying the distance between said cylinder and said slide; an arm depending below said cylinder coactable with said flaps and said slide to transversely rend a portion of cotton bat therebetween; and a bar suspended parallel to said cylinder in the path of relative movement between said cylinder and said slide.

9. In combination with a cotton condenser having means to separate cotton issuing therefrom into a plurality of continuous ribbon-like bats; a lint slide to guide one of said ribbons as a sampleable ribbon in a direction different from that of the remaining output of said condenser; a cylinder rotatably supported parallel to and in front of said slide; means for rotating said cylinder; resilient flexible flaps longitudinally secured in spaced relation about the circumference of said cylinder; means for manually varying the distance between said cylinder and said slide; a hinged bar suspended parallel to said cylinder in the path of relative movement between said cylinder and said slide; and an adjustable arm depending below said cylinder having a corrugated resilient end coactable with said flaps and said slide to transversely rend a portion of cotton bat therebetween.

GEORGE E. GAUS.
